UNITED STATES PATENT OFFICE.

OSWALD BEAUMONT CARSON, OF SOUTHBIDGE, MASSACHUSETTS, ASSIGNEE TO AMERICAN OPTICAL COMPANY, OF SOUTHBIDGE, MASSACHUSETTS, A CORPORATION OF MASSACHUSETTS.

GOGGLES.

1,113,194.

Specification of Letters Patent. Patented Oct. 13, 1914.

Application filed August 6, 1912. Serial No. 713,595.

To all whom it may concern:

Be it known that I, OSWALD BEAUMONT CARSON, a citizen of the United States, residing at Southbridge, in the county of 5 Worcester and State of Massachusetts, have invented certain new and useful Improvements in Goggles, of which the following is a specification.

My invention relates to improvements in 10 goggles, and has particular reference to an improved type of goggle which may be readily folded up to carry in the pocket when not in use.

A further object of my invention is the 15 provision of a goggle which shall be provided with rest for engaging the sides of the nose and removing the usual disagreeable pressure from the bridge of the nose.

Another object of my invention is the 20 provision of an improved folding goggle which may be readily and inexpensively constructed and in which the various parts will be so constructed and braced as to prevent damaging of the lenses or distortion of the 25 various parts of the goggle when the same is in folded position.

Other objects and advantages of my improved goggle should be readily apparent by reference to the following description 30 taken in connection with the accompanying drawings, and it will be understood that I may make any modifications in the specific details of construction shown and described within the scope of the appended claims 35 without departing from or exceeding the spirit of my invention.

Figure I represents a front view of my improved eyeglass. Fig. II represents a top plan view thereof. Fig. III represents a 40 plan view of the same with the parts in folded position. Fig. IV represents an end view of the device as shown in Fig. III. Fig. V represents a plan view of one form of blank from which the bridge and nose 45 rest of my improved goggle may be formed. Fig. VI represents an end view of a slightly modified construction of my goggle with the parts in folded position.

In the drawings, in which similar characters of reference are employed to denote corresponding parts throughout the several views, the numeral 1 designates the eye wires in which are mounted the usual lenses 2 which may be of plain or colored glass, as 50 desired, while secured to the outer portions

of the eye wires 1 are the end pieces 3, to which are pivoted the temples 4 for securing the goggle in position on the face. Although in most of the views I have shown the goggle as equipped with temples, it will be noted that in Fig. II, I have shown the same equipped with the head band 5 taking the place of the temples 4.

I have shown as suitably secured to the eye wire 1 near the upper inner portion thereof, the arm 6 which has the bend 7 formed therein to forwardly offset the portion 8 of the bridge, said portion 8 having the curled ears 9 for embracing the pinte 10, which serves to pivotally connect the 70 parts 8 on opposite sides of the goggle. Curving rearwardly and downwardly from the portion 8 forming the bridge of my goggle is a second arm 11 which is also secured to the eye wire 1. 75

In certain of the forms of my invention I have shown this arm 11 as continued in the portion 12 having a transversely extending loop formed therein and terminating in the guard 13 which has at its lower end the ear 14 also secured to the eye wire 1. It will be observed that in this form of the invention the bridge has its central portions 8 offset relative to the lenses 1 and adapted to engage each other as the eyeglasses are 80 folded to hold said lenses out of contact and prevent cracking thereof by forcing of the same together, while the guards being braced at both their upper and lower ends are so supported as to prevent distortion or accidental mashing of the same. It will be understood that if desired the guards and bridge may be made separate from each other as is illustrated in Fig. VI, this construction being similar to the preceding 85 views except in this particular. In either event the loop in the portion 12 of the arm facilitates ready adjustment of the nose piece 13 to cause the same to correctly and comfortably engage the nose of the wearer 100 of my goggle, while the ear 14 at the lower end of the guard permits of any necessary adjustment of the lower portion of the nose piece or guard, it being, of course, understood that the main necessary adjustment is 105 that of the upper portion of the guard which is effected by bending of the looped arm 12.

From the foregoing description taken in connection with the accompanying drawings, the construction of my improved gog- 110

gle should be readily apparent to all, and it will be seen that I have provided a simple, inexpensive, durable and efficient folding goggle which may be readily constructed and which is so constructed as to comfortably fit the nose of the wearer to rest on the fleshy portions of the nose and prevent undue and uncomfortable pressure on the bridge portion of the nose and which when folded is so constructed as to prevent accidental contact of the lenses which would otherwise tend to crack the same.

I claim:

1. A guard for the purpose described, comprising a bearing portion having an arm integral therewith at the upper end thereof, said arm extending rearwardly and then reversely forwardly from the guard to engage a lens attachment, the guard being further provided with a forwardly offset portion at the lower end thereof, having its terminal portion secured to a lens attachment, substantially as described.

2. A blank for a goggle bridge and nose piece comprising a central portion having ears for engaging a hinged pintle, a pair of arms extending to the opposite side of the central portion from that on which the ears are located, one of said arms being of length to engage a lens attachment, and the other of said arms being of considerably greater

length to permit of looping or reverse bending thereof, a guard depending from said second arm, and an offset attaching portion disposed at the lower ends of said guard, substantially as described.

3. A blank for a goggle bridge and nose piece comprising a bridge portion having ears for engaging a hinge pintle, a pair of arms projecting from said bridge portion and each arm being adapted to be secured to a lens, one of said arms being continued beyond its point of attachment to the lens, a guard carried by said arm, and a projection on the guard also adapted for attachment to the lens.

4. A combined bridge and nose piece for a goggle comprising a central portion adapted to engage a hinge pintle, rearwardly extending arms integral with the central portion and attached to the lens, one of said arms continuing beyond the lens in a reversely looped portion, and a guard carried by said reversely looped portion.

In testimony whereof I affix my signature in presence of two witnesses.

OSWALD BEAUMONT CARSON.
